Primary Examiner—Mark A Goodwin(74) *Attorney, Agent, or Firm*—Goodman, Allen & Filetti PLLC(57) **CLAIM**

The ornamental design for loader arms, as shown and described.

DESCRIPTION

FIG. 1 is a left front perspective view of the loader arms showing my new design in use condition.

FIG. 2 is a front view thereof.

FIG. 3 is a right front perspective view thereof.

FIG. 4 is a right side elevational view thereof.

FIG. 5 is a rear view thereof.

FIG. 6 is a left side elevational view thereof; and,

FIG. 7 is a left front perspective view thereof.

The broken line showing the machine and actuators in the drawings forms no part of the claimed design.

1 Claim, 7 Drawing SheetsFIG. 1

FIG. 2

FIG. 4

FIG. 5

FIG. 7
